UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

ORNAMENTAL EDGE-FINISHING SEAM.

1,239,675.

Specification of Letters Patent. Patented Sept. 11, 1917.

Application filed October 18, 1916. Serial No. 126,255.

To all whom it may concern:

Be it known that I, ALBERT H. DE VOE, a citizen of the United States, residing at Westfield, in the county of Union and State 5 of New Jersey, have invented certain new and useful Improvements in Ornamental Edge-Finishing Seams, of which the following is a specification, reference being had therein to the accompanying drawings.

10 The present improvement relates to ornamental edge-finishing seams for sewed articles and has for an object the reorganization of the component parts of the seam disclosed in my co-pending application Serial 15 No. 119,825, filed September 13, 1916, for the purpose of producing a seam which is less bulky and which is more highly ornamental in appearance; the lace-strip not being concealed to the same extent as in my 20 prior construction.

To these ends the improvement, in its preferred embodiment, comprises a body-fabric and lace-strip disposed in a common plane with their meeting edges in abutted relation.

25 A stay-strip is disposed beneath the marginal portion of the body-fabric with its outer edge underlapping the inner edge portion of the lace-strip. An embroidery thread is looped back and forth in "figure 8" 30 fashion across the abutted edges of the body-fabric and stay-strip and is secured in position by two spaced lines of stitches, one passing through the lace-strip and the other through the body-fabric. These lines of 35 stitches also pass through the outer marginal portion of the stay-strip. A third line of stitches serves to secure the inner edge of the stay-strip to the body-fabric.

In the drawings, Figure 1 is a plan view 40 showing the front and reverse sides of a body-fabric to which the improved seam has been applied. Fig. 2 is a cross sectional view along the line 1—1, Fig. 1.

In the embodiment illustrated, a body- 45 fabric 1, usually of knitted material, and a lace-strip or edging 2 are arranged in a common plane with the edge 3 of the body-fabric in abutted relation with the edge 4 of the lace-strip. A stay-strip 5, preferably 50 of woven fabric, the edges of which may be folded inwardly as illustrated, is so disposed beneath the body-fabric that the outer edge portion 6 underlaps the inner edge portion 4 of the edging. A covering or embroidery thread 7 of loose texture is looped 55

back-and-forth preferably in the well known "figure 8" fashion, across the abutted edges 3 and 4 and is secured in position by two spaced rows of single chain-stitches of which the outer row 8 passes through the 60 edging and stay-strip and the inner row 9 through the body-fabric and stay-strip. The inner folded edge-portion 10 of the stay-strip 5 is secured to the body-fabric by a third line of single chain-stitches 11, spaced 65 inwardly from the covering thread 7.

In the present construction the embroidery thread has a peculiar covering and concealing function due to its "figure 8" form, and will be seen to almost completely hide 70 the edge 3 of the body-fabric. When the seam is applied to the raw edge of the body-fabric the cut threads thereof will be confined and practically concealed by the embroidery thread, thus rendering it unnecessary to fold under the raw edge of the body-fabric. Any lateral strain applied to the lace-strip will be transmitted through the 75 stitches 8 and 11 to the body-fabric and there will be no tendency for such strain to distort the embroidery thread or cause the 80 stitches 9 to tear through the raw edge of the body-fabric. By abutting the meeting edges of the body-fabric and lace-strip the resultant seam is of minimum thickness and 85 the ornamental lace-strip or edging is more fully exposed to view.

Having thus set forth the nature of the invention, what I claim herein is:—

1. An ornamental edge-finishing seam for 90 sewed articles comprising, a body-fabric presenting an edge, an ornamental edging having its inner edge in abutting relation with the edge of the body-fabric, a stay-strip underlapping the abutted edge portions of the 95 body-fabric and edging, an ornamental covering thread looped back-and-forth across said abutted edge portions, and means for securing the body-fabric, edging, covering thread and stay-strip in their above defined 100 relative positions.

2. An ornamental edge-finishing seam comprising a body-fabric presenting an edge, a stay-strip applied to the under surface of the body-fabric and having its outer 105 edge projecting beyond the edge of the body-fabric, an ornamental edging having its inner edge disposed in abutting relation with the edge of the body-fabric, an embroidery thread looped back-and-forth in "figure 8" 110

- fashion across the abutted edges of the body-fabric and edging, and means for securing said edging, stay-strip and covering thread in their above defined relative positions.
- 5 3. An ornamental edge-finishing seam comprising a body-fabric presenting an edge, an ornamental edging arranged with its inner edge in abutting relation with the edge of the body-fabric, a covering thread 10 looped back-and-forth across the line of division between the body-fabric and edging at the upper side of the seam, a stay-strip having its opposite edges folded inwardly and applied to the under side of the body-fabric with its outer marginal portion underlapping the inner marginal portion of the edging, a line of stitches passing through the outer row of loops of the covering thread, the edging and the stay-strip at one side 15 20 of said line of division, another line of stitches passing through the inner row of loops of the covering thread, the body-fabric and the stay-strip at the opposite side of
- said line of division, and a third line of 25 stitches passing through the body-fabric and inner marginal portion of the stay-strip.
4. An ornamental edge-finishing seam for sewed articles comprising, a body-fabric presenting an edge, an ornamental edging having its inner edge in abutting relation with the edge of the body-fabric, a stay-strip having its outer marginal portion underlapping the abutted edge portions of the body-fabric and edging, an ornamental covering thread looped back-and-forth across 30 35 said abutted edge portions, means for securing the body-fabric, edging, covering thread and outer marginal portion of the stay-strip in their above defined relative positions, and means for securing the inner 40 marginal portion of the stay-strip to the body-fabric at a distance inwardly from the covering thread.

In testimony whereof, I have signed my name to this specification.

ALBERT H. DE VOE.
